Filed Aug. 26, 1958, Ser. No. 757,324

4 Claims. (Cl. 143—89)

This invention relates to a mitering device and particularly to a small compact mitering device for guiding a cutting blade to cut at a predetermined angle.

It is one object of my invention to provide a small, compact and extremely portable device which accurately holds a surface for guiding the blade of a cutting tool.

It is another object of my invention to provide a mitering device which is adjustable to various preset angles and which holds the angles securely by a wear-resisting connection so that play between a work-engaging member and an angle-holding member of the device is not encountered even after long periods of use.

It is another object of my invention to provide a small compact mitering device which engages work firmly and which holds the blade guiding surface not only at the appropriate angle with relation to the edge of the work, but also perpendicular to the surface that the blade is cutting.

It is another object of my invention to provide a mitering device which quickly and accurately adjusts to a preset angle in either direction.

Other objects and advantages of this invention will be apparent from the following description and the accompanying drawings in which similar characters of reference indicate similar parts throughout the several views.

Referring to the two sheets of drawings:

Fig. 1 is an isometric view of the device of my invention;

Fig. 2 is an elevational view of the assembly;

Fig. 3 is an isometric view of the work-engaging member of the assembly;

Fig. 4 is a plan view of the angle-holding member of the assembly;

Fig. 5 is a sectional view of Fig. 4 taken along line 5—5;

Fig. 6 is a sectional view of Fig. 4 taken along the line 6—6;

Fig. 7 is an enlarged isometric view of a tongue which may be used in this assembly; and

Fig. 8 is an elevation view of the assembly positioned to change the angle at which the blade guiding surface is held.

Fig. 1 illustrates various parts of the device positioned so that blade-guiding member 13 is at 45 degrees to work-engaging member 10 and is held fixed in this position by angle-holding member 12. Angle-holding member 12 is adapted with grooves for engaging a tongue which protrudes from the upper surface 24 of work-engaging member 10. It is illustrated in this view that blade-guiding member 13 protrudes beneath angle-holding member 12 the distance X which distance is equal to the thickness of the cross bar portion 15 of T-shaped work-engaging member 10. Therefore, the bottom edge of blade-guiding member 13 lies in the same plane as the lower surface 25 of T-shaped work-engaging member 10. By establishing these dimensions as here indicated, the work is engaged without wobbling by the extended length of member 13, and in addition the blade guiding surface of

member 13 is held perpendicular to the plane of the surface that is being cut. Thus, not only is the cut made at the proper angle with regard to the edge of the work but it is a square cut made perpendicularly through the top surface of the work.

In Fig. 2 there is illustrated one mode of maintaining the various members of the assembly in proper contact with each other. Pin 17 passes from the top of angle-holding members 12 completely through pin-receiving recess 18 in that member and into pin-receiving recess 22 of work-engaging member 10. The pin is preferably securely fixed in recess 22. A spring 20 is disposed in spring-receiving recess 19 and a large head on pin 17 maintains spring 20 in the recess and compressed. It is preferred that pin-receiving recess 22 is disposed immediately above the leg portion 14 of T-shaped member 10 and close to its edge so that the edge of cross bar 15 may act as a fulcrum for compressing spring 20 when angle-holding member 12 is tilted.

Fig. 3 is an isometric view of work engaging member 10 illustrating tongue member 11 protruding from the flat upper surface 24 of work-engaging member 10. Flat upper surface 24 engages flat lower end surface 23 of angle-holding member 12 and is parallel to the flat under-surfaces 25 of the cross bar 15. These surfaces are both perpendicular to the side surfaces of leg 14. The upper portion of tongue 11, as illustrated in Fig. 7, may be tapered to facilitate engaging groove 16. However, it is preferred that groove 16 be square to avoid the possibility of wobbling or play in the connection between the two. The dimension Y in tongue 11 is substantially the dimension Y of groove 16 with only sufficient difference to facilitate entry of the tongue in the groove without play. The elongated contact of tongue 11 in groove 16 provides an extremely stable engagement of the two which holds the work without wobbling or play and which endures many years of use without sufficient wear to produce a noticeable amount of play in the joint.

Figs. 4, 5 and 6 are various views of angle-holding member 12 and illustrate that angle-holding member 12 contains a flat end surface 23, a flat edge surface 22 which is perpendicular to surface 23, and a plurality of grooves 16 set at predetermined angles to flat edge surface 22 and radial to hole 18. In this embodiment, grooves 16 are disposed to hold angles of 45 degrees in either direction and 90 degrees. However, it is of course obvious that 60 degrees, 30 degrees, 22½ degrees or any other angles may be held by simply supplying the desired number of grooves at the proper angles. Grooves 16 should be deep enough to permit tongue 11 to enter completely so that surfaces 23 and 24 are in contact and, preferably, grooves 16 are enough deeper than tongue 11 is high to provide ample clearance for dirt or particles of wood or the like. When grooves 16 are cut to be mirror images of each other about a line passing through the center of hole 18 and perpendicular to edge surface 22, the blade-guiding member 13 will be adjustable to the same angle in either direction thereby greatly facilitating mitering operations. As herein illustrated, tongue 11 may be trapezoidal and assembled so that it tapers to a lesser height above surface 24 as it approaches hole 22. As illustrated in Fig. 8, the trapezoidal shape of tongue 11 reduces the distance that angle-holding member 12 need be tipped to change its position, but it does not diminish the holding quality of the connection between tongue 11 and any groove 16.

Fig. 8 illustrates the positions of the various elements of the combination of this invention relative to each other when angle-holding member 12 and work-engaging member 10 are disengaged for the purpose of changing the angle that is being held. When it is desired to change the angle being held, angle-holding member 12 is bent back

across the edge of cross bar 15 thereby raising surface 23 out of contact with surface 24. Simultaneously, groove 16 is lifted completely above tongue 11 and angle-holding member 12 is free to pivot on pin 17. In the tilted position, spring 20 is compressed to a greater extent and, upon releasing of angle-holding member 12, surfaces 23 and 24 are urged by spring 20, into contact with each other. When tongue 11 and one of grooves 16 are coincident, they will interlock and hold angle-holding member 12 and work-engaging member 10 in fixed position relative to each other as illustrated in Fig. 2.

Although the mitering device of my invention contains as essential elements a work-engaging member, an angle-holding member, a blade-guiding member and a spring loaded means for holding the work-engaging member and angle-holding members together in rotatable perpendicular relationship with tongue-and-groove interlocking means for holding them in predetermined angular relationships, many modifications of this invention are possible within its broad scope. Typical of these but not all inclusive are grooves at different angles or at more angles than those pictured, indicia marked on the angle-holding member to indicate the angle of the blade-guiding surface, different spring-loaded devices for holding surfaces 23 and 24 together, forming angle-holding member 12 and blade-guiding member 13 integral as a single piece, means integral with blade-guiding member 13 for holding a blade or for specially adapting it to specific saws, etc. This device may be made of any suitable material including wood, iron, aluminum, plastic, alloys or any mixtures of these.

It is understood that the foregoing description is merely illustrative of a preferred embodiment of the invention and that the scope of the invention is not to be limited thereto but is to be determined by the appended claims.

I claim:

1. A mitering device comprising in combination a work engaging member having a T-shaped cross section and a tongue extending longitudinally thereof and protruding from the top surface of the cross bar of said T-shaped member, an angle holding member having a flat end surface and a flat edge surface perpendicular to said end surface, a first hole drilled through said flat end surface, a larger hole than said first hole drilled coaxial with

5 said first hole through an opposing end surface, a spring in said enlarged hole and a pin holding said spring in compression and connecting said angle holding member to said work engaging member through said first hole with said flat end surface in contact with and extending beyond the top surface of the cross bar of the T-shaped member and with said flat edge surface held remote from said work engaging member, grooves cut in the flat end surface of said angle holding member, said grooves being radial to said first hole at predetermined angles with respect to said flat edge surface and of substantially the same width as said tongue and selectively receiving said tongue, and a blade guiding member attached to said edge surface protruding below said flat end surface a distance equal to the thickness of the cross bar of said T-shaped member and said pin having a shank enough smaller in diameter than said first hole and a head enough smaller in diameter than said coaxial hole to permit said angle holding member to be tilted by compressing said spring and tilting the axis of said holes enough out of parallel relationship with the axis of said pin to permit the bottom surface of said angle holding member to clear said tongue.

2. The mitering device of claim 1 further characterized in that said tongue slopes towards the pin-receiving recess of said work-engaging member.

3. The mitering device of claim 1 further characterized in that said grooves are deeper than the distance that said tongue extends above said work-engaging member.

4. The mitering device of claim 1 further characterized in that said grooves are cut in said angle-holding member to be mirror images about a line perpendicular to said flat edge surface and passing through the center of said pin-receiving recess.
